Joseph D. Wiener, Cedarhurst, N. Y.

Application December 22, 1953, Serial No. 28,176

Term of patent 3½ years

(Cl. D47—6)

To all whom it may concern:

Be it known that I, Joseph D. Wiener, a citizen of the United States of America, residing at Cedarhurst, in the county of Nassau and State of New York, have invented a new, original, and ornamental Design for Lace, of which the following is a specification, reference being had to the accompanying drawing, forming part thereof.

The drawing is a face view of the lace, showing my new design.

I claim:

The ornamental design for lace, as shown.
